DESIGN FOR A TEXTILE FABRIC

Adolph M. Kemper, Larchmont, N. Y.

Application March 16, 1944, Serial No. 112,924

Term of patent 7 years

(Cl. D92—1)

To all whom it may concern:

Be it known that I, Adolph M. Kemper, a citizen of the United States of America, residing in Larchmont, county of Westchester, and State of New York, have invented a new, original, and ornamental Design for a Textile Fabric, of which the following is a specification, reference being had to the accompanying drawing, forming part thereof, wherein width of the figure, and showing on an enlarged vertical scale that the stripes which appear gray in Figure 1 are raised as compared with the other two stripes.

A cross-sectional view taken on a vertical stripe in Figure 1, corresponding in color to the horizontal stripe 2—2, in the same figure will be similar in appearance to Figure 2.

I claim:

The ornamental design for a textile fabric, substantially as shown and described.

ADOLPH M. KEMPER.
